(57) **CLAIM**

The ornamental design for a gutter stay, as shown.

DESCRIPTION

FIG. 1 is a perspective view of a gutter stay;

FIG. 2 is a top plan view thereof;

FIG. 3 is a right side elevation view thereof, the left side being a mirror image of the right side;

FIG. 4 is a back elevation view thereof;

FIG. 5 is a front elevation view thereof; and,

FIG. 6 is a bottom plan view thereof.

The use of separations and brackets in the drawings indicate that, for ease of illustration, the precise length and width of the gutter stay is not claimed.
